WEFT REPLENISHING MECHANISM FOR AUTOMATIC LOOMS

Albert A. Gordon, Worcester, Mass., assignor to Crompton & Knowles Loom Works, Worcester, Mass., a corporation of Massachusetts

Application July 20, 1933, Serial No. 681,272

7 Claims. (Cl. 139—232)

This invention relates to automatic looms having two or more shuttle boxes on the magazine or weft replenishing end of the lay. Such a loom is shown in my prior Patent No. 1,803,181, issued

April 28, 1931, and my present invention relates to improvements in the construction and operation of the loom therein shown.

One object of my present invention is to provide a positive and accurately timed device for releasing the transerrer after the transfer operation has been completed.

Another object of my invention is to provide an improved device for directing and guiding the empty bobbin as it is ejected from the exhausted shuttle.

A third object is to provide an improved device for holding the fresh bobbin against the face of the transerrer during the transfer operation.

My invention further relates to arrangements and combinations of parts which will be herein-after described and more particularly pointed out in the appended claims.

A preferred form of the invention is shown in the drawings, in which

Fig. 1 is an end elevation of parts of a loom embodying my improvements;

Fig. 2 is an enlarged end elevation of the magazine;

Fig. 3 is a detail rear elevation of certain parts, looking in the direction of the arrow 3 in Fig. 2;

Fig. 4 is a sectional plan view taken along the line 4—4 in Fig. 2;

Fig. 5 is a sectional front elevation taken along the line 5—5 in Fig. 4;

Fig. 6 is a perspective view of certain parts, looking in the general direction of the arrow 6 in Fig. 4;

Fig. 7 is a front elevation of the device for directing and guiding the ejected bobbin;

Fig. 8 is an end view thereof, looking in the direction of the arrow 8 in Fig. 7, and

Fig. 9 is a detail plan view, looking in the direction of the arrow 9 in Fig. 7.

Referring to Fig. 1, I have shown portions of an automatic weft replenishing loom of the type shown in my prior patent and comprising a loom side 10, drop boxes 11, a two-cell magazine 12 and a transerrer 13 mounted on a rod or support 14 swinging about a fixed pivot 15.

50 A cam 16 is mounted on the usual cam shaft 17 and engages a cam roll 18 on a bell crank lever 19 mounted on a fixed pivot 20. A spring 21 holds the roll 18 yieldingly against the cam 16.

A stud 22 in the upper end of the bell crank 19 projects into an L-shaped slot 23 in a head

24 fixed to one end of a connecting rod or link 25, which in turn is pivoted at 26 to a collar 27 fixed on the transerrer support 14.

The head 24 rests on the outer end of an arm 30, mounted on a shaft 31 rotatable in fixed bearings and extending across to the other side of the loom where it has a feeler-controlled connection to intermittently actuated operating mechanism.

Under normal conditions, the parts occupy the position indicated in Fig. 1 and the stud 22 swings idly in the segmental horizontal portion of the slot 23. Upon indication of weft exhaustion, however, the arm 30 is swung upward when the stud 22 is at the front end of the slot 23, thus causing the stud to enter the vertical forward end portion of the slot 23 and to thereafter move the head 24, rod 25, support 14 and transerrer 13 rearward on the next oscillation of the bell crank 19 by the cam 16.

The magazine 12 is of the previously known type in which bobbin holders 40 are selectively movable downward to present the lowermost bobbin B in the path of the transerrer 13. The movement of the bobbin holders is controlled by a rock shaft or so-called "color slide" 41 (Fig. 80 1) movable endways by a bell crank 42 to selectively engage the one or the other of the bobbin holders and movable angularly by the arm 43 and link 44 to depress the selected bobbin holder.

All of the parts thus far described are of the usual type as is also the operating mechanism for the feeler cross shaft 31, the bell crank 42 and the link 44.

A bobbin retaining device 45 (Fig. 2) is pivoted at 46 on the magazine frame and is provided at its lower end with a resilient plate 47 (Fig. 3) having laterally spaced depending end portions 48. The end portions 48 are rearwardly curved as indicated in Fig. 2 and yieldingly engage the bobbin B as the bobbin is moved rearward by the transerrer 13 in anticipation of transfer. By providing the laterally spaced depending portions 48 the bobbin is more securely held in position and the chances of displacement during transfer are greatly reduced.

Associated with the transerrer 13 I provide a latch 50 (Figs. 4 and 6) adapted to engage a notch 51 on a stand 52. When the transerrer is moved rearward, the latch 50 positively holds the transerrer in rearward transfer position during the ensuing forward movement of the lay. A spring 53 moves the latch 50 yieldingly to holding position.

An offset arm 55 is mounted to swing with the latch 50 and is utilized for the release of the

latch, thereby permitting the return of the trans-
ferrer to normal forward position, as will now be
described.

For the purposes of such release, I provide a
5 double cam 60 (Fig. 1) on the cam shaft 17,
positioned to engage the rear end of a lever 61 at
each revolution of the crank shaft. The lever
61 is mounted on a fixed pivot 62 and is connected
10 by a link 63 to the horizontal arm 64 of
a bell crank 65 pivoted at 66 on the loom side 10.

The upper end of the bell crank 65 is positioned
to engage the end of the offset arm 55 as the
bell crank 65 moves forward, the relation of the
parts being clearly shown in Fig. 4. Such en-
15 gagement removes the latch 50 from the notch
51, thus releasing the transerrer.

It will be seen that the operation of the releas-
ing device is positive and that the timing of the
release is controlled entirely by the setting of
20 the cam 60 on the cam shaft 17. The release
of the transerrer is thus entirely independent of
the movements of the lay or drop boxes and is
more positive and dependable than in the con-
struction shown in my Patent No. 1,932,778 issued
25 October 31, 1933.

In looms of this type the pull-down connec-
tions to the harnesses commonly include a plu-
rality of light wire rods 70 which extend down-
ward just at the rear of the lay and more or
30 less in the path of the ejected bobbins. Engage-
ment of the wires by the ejected bobbins has
been found objectionable.

It has also been found that properly retarding
35 rearward movement of the butt of the bobbin
effects a rearward swinging movement of the tip
of the bobbin, which swinging movement is of
substantial advantage in withdrawing the weft
end upon the exhausted shuttle.

Accordingly I have provided the bobbin guid-
40 ing and directing device 75 shown in detail in
Figs. 7 and 9. This device comprises a box, pref-
erably of sheet metal, having a contracted de-
pending discharge portion 76 open at its lower
45 end and having an open frame 77 in its upper
front portion through which the ejected bobbins
are received.

The right hand end of the device, as viewed in
Fig. 7, is inclined forwardly, as indicated at 78
50 in Fig. 9, and is further provided with a for-
wardly and outwardly projecting wing or shield
79 positioned in front of the harness rods 70
and adapted to engage the butt of the empty
55 bobbin B as the bobbin is ejected from the shuttle.
Such engagement causes a turning move-
ment of the bobbin, as indicated by the arrow
b in Fig. 9.

This turning movement, as previously stated,
is advantageous for withdrawing the weft end
from the exhausted shuttle. The guiding and
60 directing device 75 is mounted on a cross bar 80
which in turn is firmly attached to a suitable
portion of the loom frame.

The device 75 and shield 79 thus act to protect
the harness rods 70 and to cause a desired turn-
65 ing movement of the ejected bobbin, as well as
guiding the bobbins downward to the usual bob-
bin can or receptacle.

Having thus described several features of my

invention and the advantages thereof, I do not
wish to be limited to the details herein disclosed
otherwise than as set forth in the claims, but
what I claim is:—

1. In a weft replenishing loom, a magazine, a
80 transfer member movable rearward under said
magazine to present a selected bobbin in transfer
position, means to hold said transfer member in
fixed rearward position as the lay moves for-
ward to effect the bobbin change, and a cam
85 operated device effective to thereafter release said
holding means.

2. In a weft replenishing loom, a magazine,
a transfer member movable rearward under said
90 magazine to present a selected bobbin in transfer
position, means to hold said transfer member in
fixed rearward position as the lay moves forward
to effect the bobbin change, and means inde-
pendent of the movement or position of the lay
95 effective to release said holding means after bob-
bin change.

3. In a weft replenishing loom, a magazine,
a transfer member movable rearward under said
99 magazine to present a selected bobbin in transfer
position, means to hold said transfer member in
fixed rearward position as the lay moves forward
105 to effect the bobbin change, a cam on the bottom
shaft, a lever engaged thereby, and a device oper-
ated by said lever effective to release said holding
means after bobbin change.

4. In a weft replenishing loom, a magazine,
a transfer member movable rearward under said
110 magazine to present a selected bobbin in transfer
position, a latch to hold said transfer member in
rearward position during bobbin change, and
means operated from the bottom shaft of the loom
for releasing said latch after bobbin change.

5. In a weft replenishing loom, a magazine,
a transfer member movable rearward under said
115 magazine to present a selected bobbin in transfer
position, a latch to hold said transfer member in
rearward position during bobbin change, and
means to thereafter release said latch at a pre-
determined time and irrespective of the move-
ment of the lay.

6. In a magazine, a plurality of depressible
120 bobbin holders, means to depress a selected bobbin
holder, a transfer member effective to move the
lowermost bobbin in a depressed holder to trans-
fer position, and a yielding member effective to
125 hold said bobbin against the rear face of said
transfer member as said member moves rearward,
said yielding member having substantially spaced
portions engaging said bobbin at each side of
its center of length.

7. In a magazine, a plurality of depressible
130 bobbin holders, means to depress a selected bobbin
holder, a transfer member effective to move the
lowermost bobbin in a depressed holder to trans-
fer position, and a yielding member effective to
135 hold said bobbin against the rear face of said
transfer member as said member moves rearward,
the lower end of said yielding member being
forked and having depending portions engaging
said bobbin at each side of its center of length and
140 at points substantially spaced apart.

ALBERT A. GORDON.
